FOLDING SUPPORT

Morris Lange, University Heights, and Martin Spiegel, Shaker Heights, Ohio, assignors to Superior Funeral Supply Corporation, Cleveland, Ohio, a corporation of Ohio

Application November 6, 1946, Serial No. 708,100

2 Claims. (Cl. 248—159)

1

This invention relates to supports and particularly to supports for a collapsible portable screen. Conducive to a better understanding of this invention it may be well to point out that collapsible screens used as portable backgrounds or settings in funeral parlors, or similar places, for caskets and the like usually employ two spaced supports from which the draped background or canopy is suspended. The supports are foldable and usually held in their extended condition by means of a hook, latch, sliding collar or similar manually operated locking means. If these locks should be accidentally jarred loose or be otherwise unintentionally disengaged the support will instantly collapse, carrying the draped fabric with it and possibly striking nearby persons. Furthermore even when the supports are being intentionally folded care must be taken to see that the unlocked upper sections do not fall out of control or catch the operator's fingers between the closing hinges.

It is, therefore, the primary object of this invention to provide a portable folding support that will automatically maintain itself in its extended condition without the need of any locking means.

Another object is to provide a folding support that normally maintains itself in its extended condition, so that any errors in the operator's folding technique will not cause it to collapse.

These and other objects of the invention will become apparent from a reading of the following specification and claims, together with the accompanying drawings in which the same parts are designated by the same reference characters and wherein:

Figure 1 is a side elevation, partly in section, of the folding support constituting this invention with parts of the support and carrying case broken away to show their construction and assembly, and showing certain parts in an alternate semi-folded position;

Figure 2 is an enlarged view of the base joint with parts broken away to show the construction and assembly of the joint and its relation to the spring cable when the support is in its upright position and also in an alternate semi-folded position;

Figure 3 is a view taken along the line and in the direction of the arrows 3—3 of the Figure 1;

Figure 4 is an enlarged side view of the support shoe and arm showing the arm in its upright condition;

Figure 5 is a view similar to that of Figure 4 but showing the arm in a semi-folded condition;

2

Figure 6 is a cross sectional view taken along the line and in the direction of the arrows 6—6 of the Figure 4;

Figure 7 is a right end view of a portion of the support illustrated in Figure 4;

Figure 8 is a side view of a modified form of the folding support with portions broken away to show the relative positions of the elements forming the compound spring when the device is in its folded condition;

Figure 9 is a view similar to that of Figure 8 but showing the device in its semi-folded condition;

Figure 10 is an enlarged cross-sectional view of the compound spring taken substantially along the line and in the direction of the arrows 10—10 of the Figure 9; and

Figure 11 is a view similar to that of Figure 8 but showing the folding support in its erect condition.

Referring to the drawings there is shown a folding support made in accordance with this invention. The device consists broadly of three elements or members, the base, the support including the folding arm and the operating spring. Each of these members will be described in detail and in the order set forth.

In Figure 1 reference character 11 indicates a carrying case to which the base 20 is securely fastened by suitable bolts or screws. Only the left end of the carrying case is shown for purposes of illustration since the carrying case forms no part of this invention and is merely shown to indicate one application of the invention. It is to be understood that the supports are usually used in pairs with the background suspended between them.

The base consists of a length of U shaped channel iron bent at right angles to form the bottom section 21 and the end section 25 as shown in Figures 1, 2, and 3. Both sections have paired ears which serve as means for fastening the base securely to the carrying case. Figure 3 shows the pair of ears 26 having the bolt holes 27 which are located on the end section. The bottom section also has a similarly positioned pair of ears.

The support or leg 30 and the arm 40 are made from light gage steel tubing and are hingedly connected together at the joint or shoe 33. This shoe 33 can, when the device is opened, retain the support 30 and the arm 40 in rigid vertical alignment.

The shoe is formed by splitting the end of the leg and shaping it as indicated in Figures 4, 5, 6 and 7. The shoe has an inside diameter suf-

ficient to receive the arm 40 and is open on its outer side so as to permit free pivotal movement of the arm 40. The arm has a hinge member 41 attached thereto which hinge member engages the shoe 33 by means of the pintle 43.

Reference character 42 indicates a cable terminal located on the inner wall of the tubular arm 40, opposite the location of the hinge 41. This is formed by making two parallel vertical slits in the tube wall and then pressing the stock 10 between them inward thus forming a loop thru which the spring cable 51 can be drawn and securely fastened as indicated in Figures 4, 5, 6 and 7.

The lower end of the leg 30 is joined to the base by the pintle 34 which engages the hinge member 31 as indicated in Figures 2 and 3. A guide pin 32 is positioned within the tube 30 opposite the hinge member 31 as indicated in Figure 2.

A coil spring 50 is suspended within the hollow leg 30 by means of the cable 51 which is firmly attached to the cable terminal 42. A second cable 52 is attached to the other end of the spring and then passed behind both the leg guide pin 32 and the base guide pin 22 as shown in Figures 1 and 2 and anchored on the base cable terminal 23 which is formed in the same manner as the cable terminal designated by reference character 42. The cable is drawn up tight before fastening so that the spring 50 is normally under sufficient tension to hold the support and arm in a vertical position, perpendicular to the base, as shown in Figure 1.

When the leg 30 is in the vertical position shown in Figure 1 it fits snugly between the sides of the U shaped end section 25, as indicated in Figure 3, which act as stabilizers to prevent side movement of the support. When the support is folded the leg and arm assume positions parallel to the bottom section 21 of the base 20. As the leg is folded downward the leg cable guide pin 32 moves away from the base cable guide pin 22 in a circular path, having the hinge 31 as its center.

Reference characters 30a, 32a and 52a indicate the various positions of the leg, cable guide pin and spring cable respectively, as they appear when the leg is approximately half way folded. The moving guide pin 32 carries the cable 52 with it, which in turn causes the spring 50 to stretch downward and store up energy that is used to return the leg to its vertical position as soon as the leg is free of restraint.

Similarly the folding action of the arm 40 creates tension on the cable 51 which causes the spring 50 to stretch upward as indicated in Figure 5. Since the spring 50 is under the least tension when the support is straight and upright the support will normally return to that position automatically if unrestrained.

It will now be clear that there is provided by this invention a folding support that requires no special locking means to hold the device in its upright position. Furthermore the arm and leg portions will automatically return to their upright positions if they should be accidentally flexed or thrown out of alignment, thus eliminating any possibility of the unexpected collapse of the support.

Referring to Figures 8, 9, 10 and 11 there is shown a modified form of the device which employs a compound spring, having two co-acting coils 150 and 160, as its tension element, instead of the simple cylindrical spring 50 used in the

preferred form illustrated in Figures 1 to 7 inclusive.

The modified form is intended for use with extra heavy background drapes or canopies. 5 These would require a stronger spring than is usually used in the preferred form, in order to originate the unfolding cycle.

A single coil spring of sufficient strength to accomplish this would exert too much force at the end of the unfolding cycle and would therefore cause the arm to strike against the support shoe with a sharp jolt. By dividing the forces between two co-operating spring coils the forces can be graduated to meet the changing condition of the unfolding cycle.

Except for the substitution of a graduated compound spring the modified form has the same structural features and dimensions as the preferred form.

The modified form consists of a support 130 and an arm 140 hingedly connected together at the shoe 133. The lower end of the support is hingedly joined to the base 120 which is in turn mounted in the carrying case 111.

25 The compound spring consists of an outer coil 150 which is mounted in the hollow support 130 by means of the cables 151 and 152 which engage the upper hook 153 and the lower hook 154 respectively of the coil 150. The upper cable 151 is attached to the arm 140 in the same manner as in the preferred form. The lower cable 152 is likewise engaged with the leg guide pin 132, the base guide pin 122, and the base cable terminal 123 as in the preferred form.

30 The inner coil 160 is mounted within the outer coil 150 as is clearly shown in enlarged form in Figure 10.

Reference characters 163 and 164 indicate upper and lower terminal hooks respectively of the coil 160. The inner coil 160 is attached to the outer coil 150 by means of the upper cable 161 and the lower cable 162 which are secured to the outer spring hooks 153 and 154 respectively as indicated in Figure 10.

35 Figure 8 shows the device in its folded condition with both coils under tension. The combined strength of coils 150 and 160 in this position is sufficient to quickly start the unfolding cycle when desired. It will be noted that both coils are pulling on the main cables 151 and 152.

40 Figure 9 shows the unfolding cycle at approximately the half way point. From this point on the ends of the support 130 and the arm 140 will offer less and less leverage to the force of gravity, therefore a smaller spring force will be able to complete the cycle.

45 It will be noted that the outer coil 150 has contracted, thereby permitting its hooks 153 and 154 to come close enough together to let the inner coil 160 contract until it is no longer under tension.

The outer coil 150, however, is still under sufficient tension to complete the unfolding cycle and takes over the task by itself. The cycle is 50 completed gradually and smoothly without any sudden jolt or jar, since the strength of the coil 150 is just sufficient to complete the cycle and hold the support in the erect position shown in Figure 11.

55 The inner coil 160 is now suspended from the hook 153 with its lower cable 162 hanging slack. The lengths of the cables 161 and 162 are calculated to bring the coil 160 in and out of action at approximately the half way position shown in Figure 9.

While the invention has been disclosed in its preferred form, it is to be understood that the specific embodiment thereof as described and illustrated herein is not to be considered in a limited sense as there may be other forms or modifications of the invention which should also be construed to come within the scope of the appended claims.

We claim:

1. A folding support comprising in combination, a base, a hollow support having one end hingedly mounted on the base, capable of being folded there-against, and including a transverse guide pin mounted therein opposite the hinge, and an axially extending open shoe formed on the other end thereof, a hollow arm hingedly mounted on the end of the support within the open shoe and limited to 180° flexing movement with reference to the said support by the said shoe, and a coil spring positioned within the hollow support, having one end attached to the arm opposite the hinge and the other end attached to the base after passing over the guide pin and capable of causing the support and arm to assume a co-axial position perpendicular to the base when released from their folded condition.

2. A folding support comprising in combination, a base having bottom and end sections of substantially U shaped cross section, joined at right angles to each other, a hollow support having one end hingedly mounted on the said base at the junction of the bottom and end sections,

capable of being folded there-against, and including a transverse guide pin mounted therein opposite the hinge and an axially extending open shoe formed on the other end thereof, a hollow arm hingedly mounted on the end of the support within the open shoe and limited to 180° flexing movement with reference to the said support by the said shoe, and a coil spring positioned within the hollow support, having one end attached to the arm opposite the hinge and the other end attached to the base after passing over the guide pin and capable of causing the support and arm to assume a co-axial position perpendicular to the base when released from their folded condition.
